US00D768288S

(12) **United States Design Patent** (10) **Patent No.:** **US D768,288 S**
O'Connor et al. (45) **Date of Patent:** **** Oct. 4, 2016**

(54) **DRUG DELIVERY PUMP**

- (71) Applicant: **Unitract Syringe Pty Ltd**, Sydney (AU)
- (72) Inventors: **Sean M. O'Connor**, West Chester, PA (US); **Kevin Bokelman**, San Diego, CA (US); **Ian B. Hanson**, Wayne, PA (US); **Paul F. Bente, IV**, Wayne, PA (US); **Kun-chi Wu**, Princeton, NJ (US)

- (73) Assignee: **Unitract Syringe PTY LTD**, Sydney (AU)

(**) Term: **14 Years**

(21) Appl. No.: **29/523,037**

(22) Filed: **Apr. 6, 2015**

(57) **CLAIM**

The ornamental design for a drug delivery pump, as shown and described.

DESCRIPTION

FIG. 1 is an isometric view showing the top of our design of a drug delivery pump.

FIG. 2 is an isometric view showing the bottom of the drug delivery pump of FIG. 1.

FIG. 3 is a second isometric view showing the top of the drug delivery pump of FIGS. 1-2.

FIG. 4 is an elevational view of an end of the drug delivery pump of FIGS. 1-3.

FIG. 5 is an elevational view of the opposite end of the drug delivery pump of FIGS. 1-4.

FIG. 6 is an elevational view of the right side of the drug delivery pump of FIGS. 1-5.

FIG. 7 is an elevational view of the left of the drug delivery pump of FIGS. 1-6.

FIG. 8 is a top plan view of the drug delivery pump of FIGS. 1-7; and,

FIG. 9 is a bottom view of the drug delivery pump of FIGS. 1-8.

The broken lines of FIGS. 1-9 are for the purpose of illustrating portions of the article in which the design is embodied that form no part of the claimed design.

1 Claim, 5 Drawing Sheets
